UNITED STATES PATENT OFFICE.

KAZUE AKASHI, OF ASAKUSA-KU, TOKYO, JAPAN.

DRAWING PEN OR PENCIL HOLDER.

Application filed September 2, 1921. Serial No. 498,065.

To all whom it may concern:

Be it known that KAZUE AKASHI, a subject of the Emperor of Japan, residing at No. 2 Shichikencho, Asakusa-ku, Tokyo, Japan, has invented certain new and useful Improvements in Drawing Pen or Pencil Holders (for which I have filed an application in Japan September 22, 1919), of which the following is a specification.

10 The present invention comprehends generally improvements in that class of inventions known as stationery and more particularly relates to an improved pen or pencil holder especially adapted for mechanical drafting purposes.

It is the principal aim and object of the invention to provide a device of the above character wherein improved means is employed for detachably fastening the two elements which are adapted to carry the marking material together, the means including a tongue and opening connection and a fastener, the latter normally serving to hold the marking material carrying members in operative relation but capable of being loosened to permit of disengagement of the tongue and the consequent swinging of the members so that they may be effectively cleaned without being entirely disconnected

30 from each other.

As an additional and equally important object the invention contemplates the provision of a detachable handle designed for frictional engagement with the tongue connection of the marking material carrying member permitting of the use of the handle in connection with either the pen or pencil holder.

Among the other aims and objects of this invention may be recited the provision of a device of the above character with a view to compactness wherein the number of parts are comparatively few, the construction simple, the cost of production low and the efficiency high.

Further objects as well as the nature, characteristic features and scope of this invention will be more readily apparent from the following description taken in connection with the accompanying drawings and pointed out in the claims forming a part of this invention.

The invention is clearly illustrated in the accompanying drawings, in which:

Fig. 1 is a perspective view of a drawing pen showing the marking material carrying members separated.

Fig. 2 is a longitudinal section of the same when the members are connected together,

Fig. 3 is an enlarged fragmentary longitudinal sectional detail showing the opening in one of the members which is adapted to receive the tongue on the other member,

Fig. 4 is a plan view of the two marking material carrying members with the clamping nut and the tongue disengaged from the opening so that the parts are in a position to be readily cleaned,

Fig. 5 is a perspective view of a pencil holder constructed in accordance with this invention showing the marking material carrying members separated,

Fig. 6 is a side elevation partly in section showing the members connected,

Fig. 7 is a transverse section on the line 7—7 of Fig. 6,

Fig. 8 is a transverse section on the line 8—8 of Fig. 6,

Fig. 9 is a perspective view of a handle for use in conjunction with either of the forms shown in Figs. 1 and 5, and

Fig. 10 is a side view showing the handle in engagement with the marking material carrying members of the pen.

Similar characters of reference are employed in all of the above described views to indicate corresponding parts.

Referring now, more particularly, to the accompanying drawings especially Figs. 1 to 4 there is provided a pair of members 1 and 2 for carrying marking material in the present instance ink the forward ends of the members being shaped so that when arranged in opposite positions they form the scribing points of a bowed pen. A spacing block 3 has a portion reduced and anchored in the member 2 so that its web portion extends longitudinally from the inner edge of the said member as indicated while the outer edge of the spacing block 3 is reduced to form a tongue 4 the front and rear edges of which are inclined toward the forward edge of said block. The other member 1 is provided near its inner edge with a longitudinally disposed opening the end edges of which are inclined correspondingly to the inclined edges of the tongue 4 so that the

opening may be arranged in engagement with the tongue, the outer surface of the tongue lying flush with the outer surface of the member 1 when the latter is engaged about the tongue and rests on the spacing block as indicated in Fig. 2.

In order that the members may be releasably clamped in operative relation and partly disconnected for cleaning purposes, 10 suitable fastening means is employed to coact with the tongue and opening connection and in reducing this feature of the invention to practice a fastening element 6 in the form of a threaded bolt has its inner end 15 anchored in the member 2 medially between the spacing block and the scribing end and in a manner that the shank of the bolt projects substantially at right angles from the inner surface. The member 1 is provided 20 with an opening 7 of a diameter larger than the diameter of the bolt for engagement over the bolt while the elongated end of the bolt is adjustably engaged by a suitable clamping element such as a nut 8. When 25 the opening 5 is arranged over the tongue and the opening 7 raised over the bolt 6 and the nut 8 substantially tightened the parts are held in operative relation. When however it is desired to partially disconnect 30 the members 1 and 2 the nut 8 is loosened to permit of a disengagement of the opening 5 from the tongue 4 this being due to the slightly increased diameter of the opening 7 permitting of a relative longitudinal 35 movement of the members 1 and 2. Subsequently the members may be swung to assume the position such as indicated in Fig. 4 in order that they may be readily cleaned and sharpened.

40 In Figs. 5 and 6 the invention is implied to a pencil holder, the members 1' and 2' having their forward marking material carrying end portions offset inwardly toward each other and curved transversely as indicated at 2' so as to accommodate a piece of lead. The connections between the members 1' and 2' being the same as shown for connecting the members 1 and 2 together, the parts bearing similar reference numerals with the exception that they are primed.

45 As intimated an improved handle has been employed for association with either of the arrangements shown in Figs. 1 and 5 in the present instance including an elongated body portion 9 the forward end of which is bifurcated at 10 so that the bifurcated portions are rendered resilient. These portions are reduced near their outer ends to leave shoulders 11, the reduced bifurcated 50 portions acting as jaws 12 for frictional engagement with the opposed surface of the web portion of the block 3 of either the pen or pencil holder. The handle is shown in engagement with the ink carrying members in Fig. 10. In this connection it is to

be observed that the inner portions of the members 1, 1' and 2, 2' together with the block 3, 3' form a substantial head I-shaped in cross section. As intimated when the handle is engaged the inner surfaces of the 70 jaws frictionally contact with the opposite side faces of the block 3, 3' while the upper and lower edges of the jaws contact with the opposed inner faces 1' and 2' as apparent. It is to be observed that the jaws 12 75 are of a thickness that when engaged the outer faces thereof lie flushed with the side edges of the members 1, 1' and 2, 2'.

It is believed apparent in view of the foregoing that the handle 9 is equally well 80 adapted for receiving either the ink carrying members 1, 1' or the lead carrying members 2 and 2' and that a further detailed description of the invention is entirely unnecessary. Likewise, it is also believed that the advantages of the invention 85 will be readily apparent.

Having thus fully described the invention what is claimed as new and desired to be secured by Letters Patent is:—

90 1. A drawing pen or pencil including a pair of marking material carrying members, means for releasably engaging and spacing the members, and clamping means detachably and adjustably associated with the members and coacting with the first mentioned means to releasably hold the members in operative relation or permit of them being swung with respect to each other and without being disengaged from each other, wherein 95 the members together with the engaging and spacing means therefor form a substantial head of I-shape in cross section, and a handle for detachable engagement with the head including a body portion the 100 forward end of which is bifurcated to provide resilient jaws.

95 2. A drawing pen or pencil including a pair of marking material carrying members, means for releasably engaging and spacing 110 the members, and clamping means detachably and adjustably associated with the members and coacting with the first mentioned means to releasably hold the members in operative relation or permit of them being 115 swung with respect to each other and without being disengaged from each other, wherein the means for detachably engaging and spacing the members includes a block anchored to the inner surface of one of 120 the members and having its web portion extending longitudinally from the inner edge thereof, a tongue formed on the outer edge of the web portion of the block and having its front and rear edges inclined 125 towards the forward edge of the block, and the other member being provided with an opening the ends of which are inclined correspondingly to the edges of the tongue so as to be engaged about the tongue and 130

arranged in contact with the front edge of the web portion.

3. A drawing pen or pencil including a pair of marking material carrying members, means for releasably engaging and spacing the members, and clamping means detachably and adjustably associated with the members and coacting with the first mentioned means to releasably hold the members in operative relation or permit of them being swung with respect to each other and without being disengaged from each other, wherein the means for releasably clamping the members includes a threaded bolt having its inner end anchored to one of the members, the other member being provided with an opening of a diameter greater than the diameter of the bolt, and a nut adjustably engaged with the projecting end of the bolt.
4. A drawing pen or pencil holder comprising a pair of marking material carrying members, a block anchored to the inner surface of one of the members and including a web portion projecting longitudinally from the inner edge of the said member, a tongue projecting from the outer edge of the web portion and having its front and rear edges inclined towards the forward ends of the web portion, the other member being provided with a longitudinally ar-

ranged opening near its inner edge, the respective end edges of which are inclined correspondingly to the inclined edges of the tongue so that the opening may be arranged about the tongue and the member arranged in contact with the web portion, the web portion acting to hold the members in spaced relation, a threaded bolt projecting from the member carrying the block, the member having the first opening being also provided with another opening of a diameter larger than the bolt, and a clamping member adjustably engaged with the bolt, substantially as and for the purposes specified.

5. A device as defined by claim 4 wherein the inner portions of the members and the web form a substantial head of I-shape in cross section and a handle including a body portion one end of which is bifurcated to provide resilient portions, the inner faces of the resilient portions being reduced to leave shoulders and the outer reduced resilient portions acting as jaws for removable and frictional engagement with the web portion and between the members, substantially as and for the purposes set forth.

In testimony whereof he affixes his signature.

KAZUE AKASHI.
